UNITED STATES PATENT OFFICE.

D'ORSAY McCALL WHITE, OF DETROIT, MICHIGAN.

MANIFOLD CONSTRUCTION.

Application filed May 18, 1923. Serial No. 639,802.

To all whom it may concern:

Be it known that I, D'ORSAY McCALL WHITE, a subject of Great Britain, residing at Detroit, in the county of Wayne and State 5 of Michigan, have invented certain new and useful Improvements in Manifold Construction, of which the following is a specification.

This invention relates to manifolding and 10 to motor blocks. It is the object of the present invention to obtain the best results in the operation of a motor by reason of an even distribution of the fuel to each cylinder. This is accomplished by a system of passageways 15 cast in the side of the engine block so as to completely conceal these passageways and do away with the several exposed conduits and ramifications that are ordinarily provided for this purpose in motors 20 where it is sought to get the best results in the distribution of the fuel.

This form of construction not only does away with a large amount of tubing on the exterior of the motor block which may be in 25 the way of some of the other accessories and adjuncts, but it also permits the use of exhaust heating of the passageways without using jackets and additional pipes to convey the exhaust gases to and from the intake 30 conduits.

The motor block is also provided with an arrangement whereby a certain portion of the exhaust gases are transferred from one side of the motor block to the other to heat 35 the fuel gases that are taken into the cylinder.

In the drawings:

Fig. 1 is a side elevation of a motor block showing in dotted lines, the intake ports and passageways by which the fuel gases are distributed to the six cylinders.

Fig. 2 is a sectional perspective showing how the fuel gases are distributed through the manifold.

Fig. 3 is a section taken on the line 3—3 of Fig. 1.

Fig. 4 is a section taken on the line 4—4 of Fig. 5.

Fig. 5 is a section taken on the line 5—5 of Fig. 3.

Fig. 6 is a section taken on the line 6—6 of Fig. 3.

The present system of manifolding is intended primarily for a sleeve valve motor, 55 but I do not limit myself to such a motor. The engine block shown in the drawings is

an engine block intended to use the single sleeve valve that features the "Argyle" motor—a well known British car. In this type of sleeve valve, the single sleeve valve is 60 caused to take a helical path by reason of both a reciprocating and rotating movement. The sleeve itself is not shown in the motor block, but simply the ports; there are two exhaust ports *a* on the side of each cylinder and two intake ports *b*. These ports provide large cross-sectional areas for both the admission of the fuel gases and the discharge of the burnt gases.

The engine block is cored out to provide 70 the cylinders *c*, the exhaust passages, *d*, the water passages *e*, and the intake track which is made up by the several passageways now to be referred to.

Referring to Fig. 1, it will be seen that the 75 intake passage is provided with a flange *f* to which may be bolted the conduit leading from the carburetor. The intake track is made up of a lower gallery *g*, which extends 80 across the third and fourth cylinders and terminates in the upgoing fuel shafts *h*. These connect with the upper gallery *i*, which runs across the second, third, fourth and fifth cylinders. The upper gallery connects with 85 three intermediate galleries, which run across the first and second cylinders, third and fourth cylinders and fifth and sixth cylinders. These intermediate galleries are 90 designated *j* and are best shown in Fig. 3. The upper gallery at each end connects with the intermediate point of each end gallery of the intermediate set of galleries. The 95 center of the upper gallery connects with the center of the intermediate gallery.

It will be apparent from tracing the path 100 of the fuel gases that the distance of travel to each cylinder is precisely the same. The distance of travel to one port of each cylinder will be slightly greater than to the other port of each cylinder, but each cylinder has one port in the same ratio further distant from the carburetor and consequently the effect on all the cylinders is uniform.

Seven exhaust ports are provided in the 105 side of the engine block to take care of the exhaust from the 12 exhaust ports. In the third and fifth exhaust passages, a passageway *k* leads down from the exhaust passage and in between the second and third, and fourth and fifth cylinders, respectively, to the opposite side of the engine block. This 110 clearly shown in Fig. 6. This supplies

the heating jacket *m* with exhaust gases. This forms a jacket of hot exhaust gases around the lower gallery of the manifold so as to preheat the fuel gases. The upper and intermediate galleries are heated by the water jackets *n*. Furthermore, the upper and intermediate galleries are in such close proximity to the engine cylinders that they abstract some of the heat directly from the 10 combustion chambers.

The casting is also provided with breather ports *r* at each end and these are provided with flanges and tapped bolt holes to receive any suitable fixture to be attached. 15 Suitable tapped holes *s* are also provided for extracting the core material.

From the above description it will be seen that I have provided an engine block casting which on its exterior is very plain and 20 simple, but which contains numerous passageways that are completely concealed, by which I have secured an absolutely uniform distribution of the gases through the cylinders to afford a uniform performance for 25 each cylinder, and that I have also so associated the intake track with the cylinders that the fuel gases are in a measure heated by the heat of the combustion chambers together also with the cooling water and the 30 exhaust gases. No separate conduits, so-called stoves, or other devices are necessary to use either the exhaust gases or the heated water for the purpose of preheating the fuel. This is all taken care of in the engine 35 block by the properly cored passageways. Not only does this eliminate unsightliness due to a large number of tubes, pipes, etc., on the exterior of the engine, but it also eliminates numerous joints, gaskets, etc., and 40 a larger amount of clean, clear space is provided around the engine to take the accessories and necessary adjuncts of the motor.

What I claim is:

1. In a motor block, a unit casting providing a motor block having a plurality of cylinders, and an integral manifold comprising a lower gallery, an upper gallery and a plurality of intermediate galleries, the lower gallery connecting at its ends with 50 the intermediate points of the upper gallery and the intermediate gallery connecting at intermediate points of such intermediate gallery with the upper gallery.
2. In a motor block, a unit casting cored out to provide a block having a plurality of engine cylinders and provided with intake ports at the sides of the cylinders and to provide a complete plural-galleried manifold integral with the sides of the cylinders 55 and delivering into the ports at the sides of 60

the cylinders, the galleries being arranged to secure paths of substantially equal length to each cylinder, and an engine block head arranged to removably fit on the engine block above the manifold. 65

3. In a motor block, a single engine block casting cored out to provide a plurality of cylinders having intake ports in the cylinders, a water jacket, and a complete plural-galleried manifold leading directly into the 70 cylinder ports all in one integral casting, with the water jacket around both the cylinders and the manifold, and the galleries arranged to provide a lower, upper and intermediate gallery of respectively progressively larger 75 number of passages.

4. In a motor block, an engine block casting cored out to provide a plurality of cylinders, exhaust passages, a complete plural-galleried intake manifold, and exhaust gas 80 jacket around part of said manifold and connected with the exhaust passages, all united in one integral casting. 85

5. In a motor block, an engine block casting cored out to provide a plurality of cylinders, a water jacket, a plural-galleried intake manifold, exhaust passages, an exhaust jacket around a part of said manifold and interconnected passages between the jacket and exhaust passages, all united in a single 90 casting. 95

6. In a motor block, a casting cored out to provide a plurality of cylinders, water jacket, and integral galleried intake manifold having three sets of galleries to provide 95 equal fuel gas distribution, all united in a single casting.

7. In a motor block, a casting cored out to form a plurality of cylinders, a plural-galleried manifold having a lower exhaust-heated gallery connecting at its ends with an upper water-heated gallery connecting with three intermediate galleries at intermediate points thereof, said casting having 100 exhaust passageways connecting with the exhaust jacket above referred to. 105

8. In a motor block, a casting cored out to form a plurality of cylinders with exhaust passages on one side, and an integral plural-galleried intake manifold on the opposite side, said casting provided with passageways running between the cylinders from some of the exhaust passages to the opposite side of the block and to the opposite ends of the first gallery of the intake 110 manifold. 115

In testimony whereof I have affixed my signature.

D'ORSAY McCALL WHITE.
